UNITED STATES PATENT OFFICE.

JAMES O'DONNELL, OF CENTRAL CITY, DAKOTA TERRITORY.

VALVE-GEAR FOR STEAM-ENGINES.

SPECIFICATION forming part of Letters Patent No. 253,417, dated February 7, 1882.

Application filed October 12, 1881. (No model.)

To all whom it may concern:

Be it known that I, JAMES O'DONNELL, of Central City, in the county of Lawrence, Dakota Territory, have invented a new and useful Improvement in Valve-Gear for Steam-Engines; and I do hereby declare that the following is a full, clear, and exact description of the same.

I employ two piston-valves which are rigidly connected, and hence reciprocate simultaneously to alternately open and close the ports leading to the main cylinder of the engine. Contiguous to each valve-cylinder is a steam-chest containing puppet-valves, which are operated to alternately admit steam into the small piston-chamber, from which it passes into the main cylinder.

My invention is mainly embodied in the mechanism I employ to operate said puppet-valves, and I will now proceed to describe the same in connection with other parts forming a complete engine, by reference to accompanying drawings, in which—

Figure 1 is a side view of the engine, the valve-gear being shown in such position that both sets of puppet-valves are closed. Fig. 2 is a plan view omitting the crank-shaft. Fig. 3 is a vertical section on line xx , Fig. 2. Fig. 4 is a rear view of the valve-gear, showing the position of the cams and ratchets when the segmental gear is on the half-stroke. Fig. 5 is a cross-section of the same parts as in Fig. 4. Fig. 6 is a front sectional view, showing the valve-gear and puppet-valves connected therewith, the pistons being on the half-stroke to the right. Fig. 7 illustrates the construction and arrangement of the upper portion of the valve-gear.

The letter A indicates the main cylinder of the engine, whose piston is connected by a rod, B, with the crank-arm a of a driving-shaft, C, in the usual way. Two small piston-cylinders, D D, are attached in horizontal position to the side of the main cylinder A. Such cylinders D are each provided with a reciprocating piston, E, the two being rigidly connected by a rod, F, which is attached to the short arm b of shaft C. The small crank b is set quartering with the main crank a . Both pistons E reciprocate together to alternately open and close the ports $c c$, leading from cylinders D D into the said

main cylinder. The pistons E E are located the same distance apart as the ports $c c$, so that one of the former will open one of said ports while the other is closed, which operation allows the requisite induction and exhaust of the main cylinder A.

At the inner end of each small cylinder D is arranged a steam-chest, G, which communicates therewith by a suitable port. Each steam-chest G has two apertured horizontal partitions, Fig. 3, in which two puppet-valves, H, are seated, those of each pair being connected by a vertical stem, d. The function of these valves is to control admission of steam to the cylinders D D, and thereby also to the main cylinder A. The stems d of the respective sets of valves H are pivoted to the opposite ends of a yoke or bar, I, having downwardly curved arms e. This bar is oscillated vertically by the revolution of cams K, Figs. 4 and 5, on which its ends rest, thereby alternately raising and lowering the two sets of puppet-valves H. The cams are keyed on the shafts L, and to impart the required intermittent rotary movement to the latter I employ the following-described mechanism: Ratchet-disks M are mounted first on said shafts L, and pinions N are loose thereon. The latter have spring-pawls f, which engage with teeth formed on opposite sides of the ratchet-disks M. Such engagement takes place when the pinions are rotated in one direction, but when rotated in the other the pawls ride over the teeth, and hence do not rotate the ratchets. A large segmental gear, O, is journaled on a rigid support at a point equidistant between the pinions N and meshes with both. The lower portion of the gear O is connected with the jointed end of rod P, which is attached to the same cross-head as the pistons E.

The operation of the engine is as follows: As before stated, the puppet-valves H control admission of steam to the small cylinders D D, from which it enters the main cylinder A through lateral ports c . The valves H are however raised, and the steam enters the cylinders D D a moment before the pistons E move far enough to open the ports $c c$, and hence the steam, acting meanwhile on such pistons, aids materially in rotating the crank-shaft C, and thereby in driving the engine.

In Figs. 1 and 2 the crank b is in such posi-

tion that the pistons E E are at the limit of their movement to the right. The segmental gear O has therefore swung from left to right, and in doing so has opened and closed the right-hand puppet-valves H, the left-hand valves H meanwhile remaining closed. This operation is due to the fact that when the pinions N rotate in one direction the pawls f pivoted thereby to engage with the ratchets M, and thereby 5 rotate the shafts L and cams K, thus causing the latter to raise one end of the bar I. One of the cams is raised to the vertical when the segmental gear O reaches the half-stroke, Figs. 3, 4, 5, 6; but as soon as the cam passes a little beyond the vertical the weight of the bar I carries it down into horizontal position. Thus 10 at each movement of the pistons E E to the right the right-hand cam completes a half-revolution to the right, the right-hand puppet-valves H being thereby opened and closed, and on the return-stroke (to the left) the left-hand cam, Fig. 4, is rotated to the left, thereby opening and closing the left-hand puppet-valves H. Thus one or the other cam K is always vertical, and one or the other set of puppet-valves H is always open when the segmental gear 15 completes half its movement; but both cams

are horizontal and both sets of valves are closed at the end of the movement, so that steam enters the main cylinder and works expansively. 30 In other words, steam enters the respective piston-cylinders D D on the half-stroke, and the valves H then close so as to cut off steam from the main cylinder directly after the pistons E E open the ports c c. 35

To prevent the noise and injury that would be occasioned if the valves H should seat too quickly, I employ curved plate-springs R, which are attached to a fixed portion of the engine-frame in vertical position, so as to press against 40 the end of the cam when passing from the vertical position to the horizontal.

What I claim is—

In combination with the main cylinder, cylinders D D, and the pistons E E for controlling 45 admission of steam to the former, the puppet-valves for controlling induction and exhaust of said cylinders D D, the gearing, cams, cam-shafts, and piston-rod F, substantially as shown and described.

JAMES O'DONNELL.
